KNITTING MACHINE OF THE LINKS-LINKS
TYPE

Henry Harold Holmes and Albert Henry Widdowson, Leicester, England, assignors to Wildt and Company Limited, Leicester, England, a British company

Application November 15, 1946, Serial No. 710,074
In Great Britain November 19, 1945

4 Claims. (Cl. 66—14)

1

This application is an improvement on United States Patent No. 2,366,405. According to the invention disclosed in said earlier patent a knitting machine of the links-links type includes a series of individually movable elements, operatively associated with the sliders, and in conjunction with the said elements cam means adapted to operate on all of them seriatim at a transfer location so as to effect deflection of the sliders outwards from their bed for the purpose of dividing sliders from needles in either of the needle beds during transfer of the said needles to the opposite bed.

According to the present improvement or modification means for controlling the individually movable elements are provided which are adapted to cause the said elements to dwell suchwise that sliders, actuated to transfer their needles, automatically engage associated dwelling elements and in consequence of such engagement are deflected for the purpose of liberating the needles to be transferred.

While the present improvement or modification may be adapted in conjunction with elements and sliders of any one of the forms described and claimed in Patent No. 2,366,405, it is advantageously employed in association with looping elements which form part of the equipment of the machine and which perform movements in cooperation with the needles for intended purposes, e. g. as in stitch or loop formation. Consequently, in such an arrangement the controlling means are adapted to cause the elements to dwell, at the required time between their conventional movements, in such a position as to enable them to be engaged by sliders actuated during needle transfer to achieve the necessary deflection of the sliders.

A specific example of the invention applied to a circular links and links knitting machine of the superimposed rotary needle cylinder type will now be described with reference to the accompanying drawings, wherein

Figure 1 is a vertical sectional view of so much of the said machine as is necessary to illustrate the final stage in the transference of a needle from the bottom cylinder to the top cylinder.

Figure 2 is a similar view illustrating the corresponding stage in the transference of a needle from the top cylinder to the bottom cylinder of the machine.

Figure 3 is a detail side view representing one of the double-ended needles of the machine together with an associated inside sinker and a por-

2

tion of the corresponding bottom slider, illustrating the relative positions of these during normal running, i. e. when no transfer is taking place, as will be hereinafter described.

Figure 4 is a developed view of a portion of the cam system of the machine as seen from the inside of the cam boxes, including a layout of the sinker cam system, and

Figure 5 is a further vertical sectional view taken on the line V—V in Figure 4.

Like parts are designated by similar reference characters throughout the drawings.

Referring to Figures 1 and 2, the bottom (plain) cylinder of the machine is indicated at 1, and the superimposed top (rib) cylinder at 2. The reference numeral 3 indicates one of the double-ended latch needles, while the associated bottom and top sliders whereby the said needle is actuated for knitting and can be transferred from one cylinder to the other according to requirements are designated by the numerals 4 and 5 respectively.

As in the specific example of the invention described with reference to the drawings in Patent No. 2,366,405, each of the arcuate inside holding 25 down sinkers (or web holders) 6 is provided with a lateral projection in the form of a lug 7 on one side of its hook-like operative end—beneath the nib 8 thereof. As usual the sinkers 6 operate slidably in tricks 9 in a "sinker brass" 10 fitted within the upper end of the bottom cylinder 1. Two sinker cam rings 11 and 12 are fixed one above the other, with a butt track T between them, in a sinker cup 13 fitted on the inside of the sinker brass 10. As shown in Figure 4, the track 13 is shaped more or less in the usual way at the knitting location K, or each knitting location if there is more than one, to permit plain needles to draw their loops over the breasts of the sinkers 6, and where the needles 3 rise to clear, the sinkers are moved inwards by cam action so that their nibs 8 engage the knitted web and hold it down. Thus, at the location K, the customary butts 14 on the sinkers pass through

40 a portion 15 of the track T which is so shaped that the sinkers are moved seriatim first outwards, at a point 16 just in advance of the plain stitch cam 17 and then inwards at a point corresponding to the cam portion 18 by means of which the bottom sliders 4 are actuated to cause corresponding plain needles to rise after drawing their loops.

In accordance with the present improvement or modification, the track T, after the deviation 45 just described which moves the sinkers 6 for web

holding purposes during circular knitting, is designed, as shown, so that it continues uniformly in a plane by virtue of which the sinkers are caused to dwell in the position shown in Figures 1, 2 and 3, to achieve deflection of sliders actuated at a transfer location. It should, however, be mentioned that as, in this example, the sinkers 6 are also employed as latch openers, the aforesaid deviation is a little more marked than is conventionally the case and there is a following opposite deviation of the track T at 19 before the uniform or straight segment begins. On approaching the knitting location K, or the next location, as the case may be, the track T reverts to the deviatory formation necessary to enable the sinkers 6 to function as primarily intended.

Thus, from a consideration of Figure 4, it will be realised that there is a uniform or straight segment of the track T extending right through (i.e. before, at and after) each transfer location L. The specific cam system illustrated includes a transfer cam 29 in the top cam box 21, transfer cams 22 and 23 in the bottom cam box and a further top transfer cam 24. Immediately after any slider has been advanced by a transfer cam to 25 propel a needle 3 to an extent sufficient for it to be received by an empty slider in the opposed cylinder in the usual way, the back edge of the leading end of the slider so advanced is engaged by the lateral projection 7 on the adjacent sinker 6 which latter at this stage is of course already in position to effect outward deflection of said advanced slider. In this manner the slider is liberated from the appropriate hook of the transferred needle. Thus, in Figure 1, there is shown a bottom slider 4 which has been advanced by action of the transfer cam 22 on the slider butt 24' to propel the corresponding needle 3 to an extent sufficient for it to be received by the opposed empty slider 5 in the top cylinder 2. As will be seen, the back edge of the leading end of the advanced slider 4 is in engagement with the lug 7 on the adjacent sinker 6 as a consequence of which the slider is deflected outwards to liberate the bottom hook of the needle, thereby enabling the latter to be retracted into the top cylinder. Similarly, in Figure 2, the top slider 5 has been sufficiently advanced by one of the top transfer cams to enable the needle 3 to be received by the bottom slider 4, the adjacent sinker having been previously positioned in the manner hereinbefore described to effect outward deflection of the top slider. Figure 3 indicates the relative disposition of the needles and associated sliders and sinkers when transfers of needles are not taking place.

The bottom transfer cam 22 is a fixed one which functions in conjunction with a patterning wheel (not shown), the butts 24' of selected bottom sliders being acted upon and raised by the cam 22, while the remaining butts 24' pass tidily beneath this cam.

As described in the Patent No. 2,366,405 the needles 3 are equipped with latches 26 and the upper and lower edges of the lug 7 on each sinker 6 are chamfered or bevelled so as to provide thin latch opening edges suitable to be presented between the hooks and latches of needles with closed latches as said needles are advanced, say, for instance, for transference, or for clearing after knitting or for restoration to a normal position after casting off. In association with the top sinker cam ring 12, at the location 19 where opening of needle latches for any of the purposes mentioned is to be effected, there is provided a movably mounted spring-controlled cam part 27

which is arranged for action on the sinker butts 14 and yet is capable of yielding to a small extent in an upward direction to permit slight outward movement of any sinker whose latch opening lug is acted upon by a needle hook, substantially as and for the purpose described in Patent No. 2,366,405.

The needles, sliders and sinkers travel in the direction of the arrow A in Figure 4.

To facilitate an understanding of Figure 4, it ought to be explained that this figure is a developed view of the cam systems and the top and bottom sinker cams of the machine, as viewed in the direction of the arrow B in Figure 1, and with the cylinder 1, the sinker brass 10 and the sinker cup 13 removed for the sake of clarity.

Thus, as will be appreciated, the important distinguishing feature of the present improvement or modification is that the individual sinkers are caused to dwell in contradistinction to being moved seriatim at a transfer location as described in the parent specification.

The extent to which the elements project—in relation to the sliders—when they dwell, may depend on the character of the needles and sliders or/and the elements. For instance, in the case of sliders with hook-like clutches an appreciable amount of deflection is required to liberate the needles. Accordingly the controlling means may be designed so that the projection of the dwelling elements in relation to sliders actuated for transferring is such that with elements or/and sliders furnished with formations not of critical dimensions the whole of the outward deflection of the sliders is effected in consequence of the projective positioning of the elements. Alternatively the leading ends of the sliders may be enlarged or the dimensions of the said formations may be increased with commensurate decrease of the projective positioning of the dwelling elements. Again, with sliders furnished with angular clutches—i. e. clutches having oppositely bevelled or mitred edges—which require less deflection to liberate the needles, the controlling means may be adapted to effect correspondingly less projective positioning of the elements, without increase of the dimensions of the formations on the said elements or/and the companion sliders, since in that case the hooks of the needles, if only partially liberated, act on the sliders, when engaged with and pulled endwise by the opposite sliders, to cam the partially deflected sliders outwards to complete the deflection. Further, as regards sinkers or web holders employed also as deflectors, and with needles of the character having a pronounced middle bulge or bend, it is desirable, if not essential, to impart relieving movement to the sinkers or web holders after they have performed their normal functions at a knitting location, to relieve the strain on the loops on the needles at a transfer location in order to avoid bursting of the said loops as they pass over the middle bulge or bend. Consequently advantage may be taken of this relieving movement to position the dwelling sinkers or web holders so that sliders actuated for transference of needles are automatically deflected outwards.

What we claim then is:

1. In a knitting machine, in combination, a rotary plain needle cylinder, a superimposed rotary rib needle cylinder, doubled-ended needles for operation in said cylinders, sliders for operating the needles, means at respectively different locations for effecting transference of needles

from one cylinder to the other, a circular series of curved holding down sinkers each furnished with an operating butt and having a lateral projection on one side of its operative end for action upon companion sliders, and sinker cam rings providing between them a track for the butts, the said rings being so shaped as to provide in the track, in addition to the usual deviation which moves the sinkers for web holding purposes, a straight portion extending uniformly through the transfer locations in a plane by virtue of which the sinkers are caused to dwell in a position at which they automatically engage those sliders actuated to transfer their needles for the purpose of causing outward deflection of the said sliders to liberate them from the said associated needles.

2. In a knitting machine, in combination, two opposed needle beds, double-ended needles for operation in said beds, sliders for operating the needles, means at respectively different locations for effecting transference of needles from one bed to the other, a series of individually movable elements for cooperation with sliders during a needle transfer action, each of said elements being furnished with an operating butt and having at its operative end a formation for action upon companion sliders, and cam parts providing between them a track for the operating butts, the said parts being so shaped as to provide in the track a straight portion extending uniformly through the transfer locations in a plane by virtue of which the elements are caused to dwell in a position at which they automatically engage those sliders actuated to transfer their needles for the purpose of causing outward deflection of the sliders to liberate them from the said associated needles.

3. In a knitting machine, in combination, a rotary plain needle cylinder, a superimposed rotary rib needle cylinder, double-ended latch needles for operation in said cylinders, sliders for operating the needles, means at respectively different locations for effecting transference of needles from one cylinder to the other, a circular series of curved holding down sinkers each furnished with an operating butt and having a lateral projection on one side of its operative end for action upon companion sliders, and sinker cam

rings providing between them a track for the butts, the said rings being so shaped as to provide in the track, in addition to the usual deviation which moves the sinkers for web holding purposes, a straight portion extending uniformly through the transfer locations in a plane by virtue of which the sinkers are caused to dwell in a

position at which they automatically engage those sliders actuated to transfer their needles for the purpose of causing outward deflection of the said sliders to liberate them from the said associated needles, the aforesaid lateral projections being also so formed as to present latch opening edges to needles in both cylinders, in the path of the needle latches at a location where closed latches are to be opened when needles are advanced, so that by reason of such advance appropriate latches are brought into engagement with the opposing edges and consequently opened.

4. In a knitting machine, in combination, a rotary plain needle cylinder, a superimposed rotary rib needle cylinder, double-ended latch needles for operation in said cylinders, sliders for operating the needles, means at respectively different locations for effecting transference of needles from one cylinder to the other, a circular series of curved holding-down sinkers each furnished with an operating butt and having a lateral projection on one side of its operative end for direct contact with the back edges of the companion sliders, the said lateral projections being also so formed as to present latch opening edges to needles in both cylinders, in the path of the needle latches at a location where closed latches are to be opened when needles are advanced, sinker cam rings providing between them a track for the butts, the said rings being so shaped as to provide in the track, in addition to the usual deviation which moves the sinkers for web holding purposes, a straight portion extending uniformly through the transfer locations in a plane by virtue of which the sinkers are caused to dwell in a position at which they automatically engage those sliders actuated to transfer their needles for the purpose of causing outward deflection of the said sliders to liberate them from the said associated needles, and a part which is associated with the sinker cam rings and yieldingly mounted so that any element acted upon by a needle hook will push on said part and cause it to yield, for the purpose herein specified.

45 HENRY HAROLD HOLMES.
